WATER PUMPING DEVICE FOR OIL GAS WELLS

Original Filed Jan. 18, 1923

Fig. 1.

Fig. 2.

UNITED STATES PATENT OFFICE.

WILLIAM C. RUSSELL, OF WEST SUNBURY, PENNSYLVANIA.

WATER-PUMPING DEVICE FOR OIL-GAS WELLS.

Application filed January 18, 1923, Serial No. 613,543. Renewed May 25, 1926.

This invention relates to gas wells, and has special reference to a water pumping device for oil gas wells.

One object of the invention is to provide an improved and simple device for removing water from gas wells which can be readily manufactured at low cost and which may be inexpensively installed and operated.

A second important object of this invention is to provide a simple and improved device of this character which will be operated by the pressure of the gas within the well.

With the above and other objects in view, as will be hereinafter apparent, the invention consists in general of certain novel details of construction and combinations of parts hereinafter fully described, illustrated in the accompanying drawings and specifically claimed.

In the accompanying drawings like characters of reference indicate like parts in the several views, and:

Fig. 1 is a section through a gas well showing the device in position therein.

Fig. 2 is an enlarged detail vertical section through the device.

In the embodiment of the invention as illustrated in the accompanying drawings, it will be seen that there is shown a drilled gas well 10, having the upper part provided with the usual casing 11, which projects slightly above the ground line 12, and is capped as at 13. The invention itself comprises a length of pipe or tubing 14 which I prefer to have of one-half inch pipe. On the outer end of this length of one-half inch pipe is fitted a reducing coupling 15 by means of which the pipe 14 may be connected to a string of three-quarter inch piping 16 projecting upward through the cap 13. The pipe 14, which I preferably term the jet barrel, is capped at its lower end with a sleeve 17 screwed thereon, this sleeve being closed below and provided with lateral perforations or openings 18. The closure at the bottom of the end of the sleeve is provided with a screw threaded opening, and in this screw threaded opening is screwed a jet nozzle 19 which, by means of its threaded connection with the cap 17, may have its upper or outlet end 20 positioned in desired relation to the openings 18. This jet nozzle 19 is connected by the elbows 21 and nipple 22 with a gas intake pipe 23 which extends

for enough up the well to be above the high water line 24, in the bottom of said well. This pipe 23 is capped at its upper end to prevent anything falling therein, and is provided with lateral perforations 25 for the admission of gas.

In operation the device is inserted in the well in the position shown in Figure 1 so that gas under pressure in the well may enter the perforations 25 and flow out through the nozzle tip 20. This gas will thus act as a motive fluid of an ejector, the effect being to first blow out the water standing in the pipes 14 and 16, and then to draw any water through the perforations 18 by reason of the barrel vacuum created just below the tip of the nozzle 19. It will be observed that different conditions in different wells require different distances to be maintained between the tip 20 and the perforations 18, and to this end the nozzle 19 may be adjusted to obtain the maximum effect by screwing the same in or out of the collar 17.

There has thus been provided a simple and efficient device of the character described, and for the purpose specified.

It is obvious that minor changes may be made in the form and construction of the invention without departing from the material spirit thereof. It is not, therefore, desired to confine the invention to the exact form herein shown and described, but it is desired to include all such as properly come within the scope claimed.

Having thus described the invention, what is claimed as new, is:

1. In a device of the kind described, a barrel, a cap screwed at the lower end of said barrel, the bottom of said cap being provided with a centrally disposed screw threaded opening and the side wall of said cap being provided with a series of radially extending perforations, a jet nozzle threaded in the opening in the bottom of the cap and adjusted longitudinally with respect to said cap by rotation therein, and a supply pipe connected to said nozzle and extending up along the side of the barrel sufficiently high to reach the gas space of the well above the high water line.

2. In a device of the kind described, a barrel, a cap screwed at the lower end of said barrel, the bottom of said cap being provided with a centrally disposed screw threaded opening and the side wall of said

2
cap being provided with a series of radially extending perforations, a jet nozzle threaded in the opening in the bottom of the cap and adjusted longitudinally with respect to said cap by rotation therein, and a supply pipe connected to said nozzle and extending up along the side of the barrel sufficiently high

to reach the gas space of the well above the high water line, said supply pipe having its upper end capped and being provided with lateral perforations adjacent said upper end. 10

In testimony whereof I affix my signature.

WILLIAM C. RUSSELL.
